CLAIM

We claim the ornamental design for a flame shield, as shown and described.

DESCRIPTION

FIG. 1 is an isometric perspective view of a flame shield, showing our new design.

FIG. 2 is an isometric top view of the flame shield.

FIG. 3 is an isometric bottom view of the flame shield.

FIG. 4 is an isometric front elevational view of the flame shield, the rear side being a mirror image thereof; and,

FIG. 5 is an isometric left elevational view of the flame shield, the right side being a mirror image thereof.
